[57] CLAIM

The ornamental design for a double triggered reel seat, as shown and described.

DESCRIPTION

FIG. 1 is a perspective view of a double triggered reel seat, showing my new design;

FIG. 2 is a left side elevational view thereof;

FIG. 3 is a top plan view thereof;

FIG. 4 is a front elevational view thereof;

FIG. 5 is a rear elevational view thereof; and

FIG. 6 is a bottom plan view thereof.

The broken line showings of part of a fishing rod, and a fishing rod handle are for illustrative purposes only and form no part of the claimed design.
